GRAIN BINDER

Filed Dec. 19, 1929

UNITED STATES PATENT OFFICE

ROBERT C. LIVESAY, OF MOLINE, ILLINOIS, ASSIGNOR TO DEERE & COMPANY, OF MOLINE, ILLINOIS, A CORPORATION OF ILLINOIS

GRAIN BINDER

Application filed December 19, 1929. Serial No. 415,179.

My invention relates to harvesting machinery and more particularly to that part of the mechanism of a harvester and binder by operation of which the gavels are formed and tied in bundles, and the object of my invention is to hold the bundle under compression after it is bound and the needle has receded for a limited distance in returning to an inoperative position.

10 Referring to the drawings in which similar numerals indicate identical parts:

Figure 1 is a detail side elevation of as much of a binding mechanism necessary to illustrate the application of my invention 15 with the needle and my device in inoperative position;

Figure 2 is a similar view with the parts as located when a bundle is being compressed and bound;

20 Figure 3 is an enlarged detail section on the line 3—3 of Figure 2;

Figure 4 is an enlarged detail section showing the manner of holding the supplemental compressor arm in raised position; and,

25 Figure 5 is an enlarged detail section on the line 5—5 of Figure 1.

With the exception of the compressor trip arm 1 the parts are housed below the binder deck 2. The compressor trip arm 1 is of a common type and is secured on the compressor trip shaft 3. The needle 4 is rigidly mounted on the needle shaft 5 and is of the conventional form but provided with a prong 6 extending rearwardly from the shank 7 of the needle and concentric with the axis of the latter. A supplemental compressor arm 8 is rotatably mounted on the needle shaft 5 and has, projecting rearwardly therefrom, an arm 9 in which is a slot 10 concentric with the needle shaft 5. A stud or pin 11 is attached to the shank 7 of the needle and projects through the slot 10 being secured therein by the head 12.

40 The bar 13 is a part of the harvester frame and securely bolted thereon is a bifurcated

bracket 14 the arms of which are connected by an integral part 16 having a groove 17. Between the lower ends of the bracket arms, and projecting below them, is a rocking member 18 pivotally secured in place by a bolt 19 50 which extends through the arms and the member 18. The upper end of the member 18 is enlarged to form a cam 20 having a groove 21 in opposition to the groove 17. A rod 22, curved concentric with the prong 6, 55 is pivotally attached at one end to the termination of the arm 9 and extends between the cam 20 and the part 16 and fits loosely in the grooves 17 and 21 when the needle 4 and the compressor arm 9 are at rest or being raised. 60

In the operation of a binding mechanism, when the needle has been raised so that the twine encompasses the bundle and is presented to the knotter bill, the bundle is formed and compressed between the needle 65 4 and the compressor arm 1; the needle, however, begins its backward movement before the knotter bill has made more or less than a quarter turn, consequently sufficient twine to complete the knot must be taken from the 70 twine holder and that around the bundle. Now as the compression decreases, by recession of the needle, it is very evident that the swell of the bundle subjects the twine to a very severe strain which often results in imperfect operation of the tying mechanism. 75

To hold the bundle in compression until it is tied I utilize my invention which comprises the mechanism heretofore described and which operates as follows:—

As shown in Figure 1 the parts are in a normal position of rest while grain is accumulating against the compressor arm 1. When the binding mechanism is tripped to operate, the needle 4 rises carrying with it 85 the stud 11, the latter traveling in the slot 10 until it reaches the upper end of the slot and contacts with the arm 8, resulting in the arm rising with the needle and acting therewith in compressing the bundle, the rod 22 90

moving freely in the grooves 17 and 21 of the parts 16 and 20, respectively.

The member 18 is movable freely on its pivot consequently when the needle recedes the compressor arm 8 is held firmly against the swell of the bundle by the cam 20 clamping the rod 22 against the part 16, the action of the parts being so timed that the compressive action of the arm 8 is retained until the tying of the bundle is completed when the pressure against the arm 8 ceases by ejection of the bundle in the usual way. At the instant of discharge of the bundle the needle 4 has receded sufficiently to contact the rounded end of the prong 6 with a pin 23 on the member 18 and as the recession of the needle continues the member 18 is rocked, to break the clamping action of the cam 20 against the rod 22, by the pin 23 traveling over the rounded point of the prong and the inner face thereof, so that the rod 22 is again freely movable between the part 16 and the cam 20, consequently the compressor arm 8 falls by gravity to its position below the deck 2.

25. What I claim is—

1. In a grain binder, the combination of a binding mechanism including a trip and compressor arm and a needle adapted to be actuated cooperatively to compress a gavel, 30 a supplemental compressor arm pivotally mounted upon the axis of the needle and movable to compressive action against a gavel by upward movement of the needle, a rearward extension of said arm, a curved member 35 pivotally attached to said extension and concentric with the axis of the needle, a locking device on the binder frame in constant engagement with said member and automatically operative to grip said member and hold said arm in compressive action against a gavel during a portion of the retrograde movement of the needle, and means on the needle extending rearwardly therefrom and operative by retrograde movement of the 40 needle to disengage said member from the locking device and permit said arm to recede from the gavel and downward to inactive position.

2. In a grain binder, the combination of a 50 binding mechanism including a trip and compressor arm and a needle adapted to be actuated to cooperatively compress a gavel, a supplemental compressor arm mounted upon the axis of the needle, a slot in said arm concentric with said axis, a stud on the needle engaging with the slot and contacting with the upper end thereof to carry said supplemental arm to compressive action against a gavel when the needle rises, a locking device on the 55 binder frame, means pivotally attached to the supplemental compressor arm in constant engagement with said locking device and automatically gripped thereby to hold said arm at the limit of its compressive action, and 60 means on the needle operative by the retro-

grade movement thereof to disengage said lock and member and permit said supplemental arm to recede from the gavel and downward to inactive position.

3. In a grain binder, the combination of a 70 binding mechanism including a trip and compressor arm and a needle adapted to be actuated to cooperatively compress a gavel, a supplemental compressor arm mounted upon the axis of the needle, a rearward extension of 75 said arm, a slot in said supplemental arm and its extension, a stud on the needle engaging with the slot and contacting with the upper end thereof to raise said supplemental arm by the rise of the needle into compressive 80 action against a gavel, a locking device on the binder frame, a rod pivotally attached to said extension and in constant engagement with the lock and adapted to be gripped thereby to hold the supplemental arm at the limit of 85 its compressive action, and a prong extending rearwardly from the shank of the needle and adapted to trip said locking device by a limited retrograde movement of the needle and disengage said rod and locking device to permit 90 said supplemental arm to recede from the gavel and downward to inactive position.

4. In a grain binder, the combination of a 95 binding mechanism including a trip and compressor arm and a needle adapted to be actuated to cooperatively compress a gavel, a supplemental compressor arm pivotally mounted on the axis of the needle and movable to compressive action against a gavel by upward 100 movement of the needle, a rearward extension of said arm, a locking device on the binder frame, a rod pivotally attached to said extension and bent concentric to the axis of the needle and in constant engagement with the locking device, said locking device normally 105 inactive and operating by the needle as the latter rises to grip said rod and hold said arm in compressive action against a gavel, and a prong extending rearwardly from the shank 110 of the needle concentric with said axis and adapted to trip said locking device by a limited retrograde movement of the needle to permit said supplemental arm to recede from the gavel and downward to inactive positions.

5. In a grain binder, the combination of a 115 binding mechanism including a trip and compressor arm and a needle adapted to be actuated to cooperatively compress a gavel, a supplemental compressor arm mounted upon the axis of the needle and connected with the needle to rise therewith into compressive action on a gavel, a bifurcated bracket mounted on the binder frame, a rearward extension of said arm, a curved rod pivotally attached to said extension and projecting rearwardly 120 between the sides of the bracket and freely movable therein when the supplemental arm is in an inoperative position or being raised to compressive action, a swinging member pivotally supported on said bracket and hav- 125

ing a cam at its upper end to grip said rod against the upper end of the bracket and hold said supplemental arm from receding from a compressing position, a pin on the free end of said member, and a prong extending rearwardly from the shank of the needle and operating by a retrograde movement of the needle to contact with said pin and rock said member whereby the grip of the cam upon said rod is released and the supplemental arm returns to its inactive position.
